(57) **CLAIM**

The ornamental design for a wrist ankle weight as shown and described.

DESCRIPTION

FIG. 1 is a front, right, and top perspective view of a wrist ankle weight showing my design;

FIG. 2 is a rear, left, and bottom perspective view thereof;

FIG. 3 is a front elevational view thereof;

FIG. 4 is a rear elevational view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front and top perspective view showing the wrist ankle weight in a position of use.

The broken lines depict portions of the wrist ankle weight that form no part of the claimed design.
